ADDING-MACHINE.

1,093,424.

Specification of Letters Patent. Patented Apr. 14, 1914.

Application filed December 30, 1908. Serial No. 470,073.

To all whom it may concern:

Be it known that we, JOHN PIRRONG HUNTER and HENRY KÜNTZLER, citizens of the United States, and residents of Wilkes-Barre, in the county of Luzerne and State of Pennsylvania, have invented certain new and useful Improvements in Adding-Machines, of which the following is a specification.

This invention relates to adding machines and similar mechanisms adapted to be intermittently energized by a motor taking its power from a source of electrical energy through conductors and its novelty consists in the construction and adaptation of the parts, as will be more fully hereinafter pointed out, and particularly in the means provided automatically to lock the mechanism of the adding machine against accidental actuation when the motor is not energized, and to warn the operator by a visible or audible signal, or both, when the current is turned on to the motor serving to actuate the machine, and to indicate clearly when the motor is not energized.

In the following specification the invention is shown and described as applied to the Wales adding machine and to a peculiar driving mechanism attached thereto, but it will be understood that it is equally applicable to other forms of driving mechanism and power transmitting devices, or other adding machines.

The driving mechanism herein disclosed is described and claimed in a co-pending application for Letters Patent of the United States filed December 28, 1908, Serial No. 469,529, which, in brief, comprises a multiple crank moved from the intermediate shaft above referred to, a loosely traveling member in the form of a sliding rack bar moved by but not connected to the multiple crank and a gearing moved from the rack bar to which also it is not connected and which gearing actuates the operating rock shaft of the machine.

In the drawings, Figure 1 is a top plan view of the front portion of an adding machine provided with our invention; Fig. 2 is a side elevation of the parts shown in Fig. 1, together with the mechanism below the base of the machine, a portion of the machine being broken away to show concealed parts; Fig. 3 is a perspective detail of the

motor actuator control arm; Fig. 4 is an enlarged section through the switch box and a top plan view of the parts beneath the section plane showing the positions of the parts when the current is on; Fig. 5 is a similar view showing the position of the same parts when the current is off; Fig. 6 is a section on the plane of the line 6—6 in Fig. 5; Fig. 7 is a diagram of the wiring of the machine; Fig. 8 is a side elevation of the motor actuator controller, Figs. 9 and 10 are respectively front and rear elevations of the same, and Fig. 11 is a side elevation partly in section showing the clutch mechanism intermediate the motor and the adding machine.

Referring to the drawings, 1 is the base of an adding machine and 2 is a part of one of its side frames, of which there are two, one on each side of the machine; 3 is a transverse shaft through the oscillation of which the mechanism of the adding machine is operated.

Mounted on a pair of elbow levers 20 which move together is a depressible bar 21 adapted to move vertically. This bar is provided with a pair of depending sleeves 4 which engage the upper ends of the levers 20 and may thus be readily removed therefrom. These levers are adapted to swing on pivots 22 projecting from the frame of the machine. At their lower extremities they are coupled by a link 23 so that they will move together and to one of them at 24 is pivoted a link 25 which in turn is pivoted to a crank arm 26 rigidly secured to a rock shaft 27 to the other end of which is secured a crank 28 which in turn is pivoted to a vertically placed link 29 pivoted at its lower end to a crank 30 mounted on a rock shaft 31 which, in turn, is connected to the devices by which the function of the holder of the power transmitting mechanism is interrupted and restored.

It will be understood that the power transmitting mechanism disclosed is not a part of our invention but is similar to that shown and described in Letters Patent No. 902,103, issued October 28, 1908, to Charles N. McFarland. In brief, however, as is shown in Fig. 11, the motor 100 drives shaft 101 carrying a worm 400. Worm 400 drives a wormwheel loosely mounted upon shaft 105. This wormwheel carries a drum 401 with a finished inner cylindrical surface. Within

this drum is located a pair of semicircular friction arms 403 pivotally mounted at 402 to a plate fastened to shaft 105. This plate also carries a pair of lugs, one of which is shown at 409. A spring 411 is attached to each of these lugs and to a stud 410 upon the friction arms 403, the springs tending to force the arms outward against the inner surface of the drum 401. This thrust of the springs is normally resisted by means of suitable pins 413 fastened to the arms near their extremities and engaging slots in a rotating piece carrying diametrically opposed ears 404. This piece is in turn normally held from movement by a detent 405 engaging one of said ears. This detent is mounted upon arm 406 which is fastened to and rocks with shaft 31 when the actuator bar 29 is depressed. The release of the ear 404 from the detent allows the spring 411 to bring the friction arms into contact with the continuously rotating drum 401. All of the parts mounted upon shaft 105 thereupon rotate as a unit. In addition to those already described, a cam member 407 is fastened to the shaft 105. After the clutching action described above has taken place and the shaft 105 has rotated several degrees, a raised part of cam 407 strikes a roller 408 carried by an arm 414 fastened to rock shaft 31 and moves it outward. This movement at the same time forces arm 406 inward to a position in which the detent 405 will engage the second ear 404 when the shaft has completed one-half of a revolution. The arresting of movement of the ear-carrying piece effects by means of the pin and slot connections above described a withdrawal of the friction arms from engagement with the rotating drum against the pressure of the springs attached to the arms and in this way the driving and the driven parts are completely disengaged and the clutch is in readiness for a second actuation.

Mounted on the intermediate shaft 105 is a multiple crank 60 having a plurality of arms 61, each provided at its extremity with a roller 62.

63 is a roller adapted to turn on a pin or bearing projecting from a fixed part of the clutch inclosure. 64 is a similar roller adjustably attached also to the clutch inclosure. Mounted to be reciprocated between these rollers, by which it is guided and which limit its movement is a loosely traveling rack bar 65 provided with a slot 66 adapted to engage the roller 63. It also has a depending arm 67 adapted to be engaged by the rollers 62 on the arms 61 of the multiple crank 60 and is also provided with a flange 68 adapted to engage the roller 64. At its upper front edge it has a series of teeth 69 constituting a rack, which teeth are adapted to engage the teeth 70 of a gear 71

operatively connected to the shaft 3 which it oscillates. A spring indicated at 600 is fastened to the bar 65 and to a fixed point on the clutch inclosure and serves to retract it to position after movement.

In the operation of the machine after an item has been enumerated in the usual manner by the depression of the numeral keys with which it is provided (and which are not shown), the actuator bar 21 is depressed by the operator. This moves the link 25 to oscillate the crank 26 and rock the shaft 27 which in turn lowers the arm 28 and link 29 and rocks the shaft 31 to couple the intermediate shaft 105 to the motor whereby the multiple crank 60 is rotated and the rack bar 65 is moved to actuate the machine.

None of the parts above described constitute any part of our present invention, but their general construction, relation and mode of operation must be understood in order that the particular invention under discussion can properly be appreciated.

Concealed at a point at the front of the base of the machine convenient to the operator is a box 8 made of insulating material and adapted to contain an electrical switch 80 through which an electric current is supplied from an ordinary lamp socket to the motor circuit. It comprises a beam 81 adapted to oscillate on a pivot 82 and moved by two rods, one 83 pivoted to the beam 81 at 84, and the other 85 pivoted to the beam 81 at 86. The rod 83 is provided with a push button 87, and the rod 85 is provided with a similar push button 88, each projecting through suitable apertures in the front of the box 8 and the base of the machine. These buttons are made of any suitable insulating material, as hard rubber.

Electrical conductors 90 and 91 leading from and to a source of electrical energy (not shown) supply current to the motor 100. They are in circuit with the switch 80 through the contact posts 93 leading from the conductor 90 and adapted to contact with a wing 95 on the beam 81 and through the similar post 96 leading from the conductor 91 and adapted to contact with the wing 97 on the beam 81. When the beam and buttons are in the positions shown in Fig. 4 the current is on and the motor 100 is energized, and when they are in the positions shown in Fig. 5, the current is off and the motor is not energized.

Secured to one of the buttons 88 is a rod 200 having an extension 201 of suitable insulating material, for instance, hard rubber, adapted to pass through an aperture in the rear of the box 8. To the outer extremity 125 of this extension there is secured an elbow 202 provided with a catch 203 adapted to engage an extension latch 204 projecting from the link 29 of the actuator of the adding machine. In the line of the conductor 130

90 and in circuit with the motor there is inserted an incandescent electric light indicated at 210. It is obvious that when the current is turned on by the movement of the switch 80, the light will glow and shine so long as the parts remain in that position.

Projecting from the connection 291 is a trip arm 212 adapted to engage one elbow 213 of a bell crank lever pivoted at 214 to any convenient part of the machine and the other elbow 215 of which is provided with a clapper 216 adapted to strike a gong 217, the elbow lever being provided with a spring indicated at 218 to restore it to position after actuation.

Supposing that the conductors 90 and 91 are suitably supplied with energy and the parts of the switch are in the positions shown in Fig. 4, it is obvious that the current can pass from the conductor 90 through the post 93, wing 95, beam 81, wing 97, post 96 and conductor 91 and thus complete the circuit, so that the motor is energized and the light 210 is illuminated. When the parts are in this position, if the arm 21 is depressed, and there is no other obstacle placed in the way of the movement of the crank 30 actuated from the link 29, then the depression of the arm 21 will couple the intermediate shaft 105 to the motor 100, cause the rotation of the multiple arm 60, the movement of the rack 65 and the consequent actuation of the machine through the gear 71. If, however, the push button 88 is pushed inwardly, the parts are caused to assume the positions shown in Fig. 5, when it is evident that the circuit will be broken and the motor will cease to be energized and the light will be extinguished. At the same time the movement of the extension 201, through the action of the button 88, will move the catch 203 under the latch 204 of the link 29, and thereafter the link 29 and consequently the depressible arm 21 cannot be moved downwardly and the adding machine cannot be coupled to the motor.

It is further obvious that when the current is again turned on, by the movement of the push button 87, the trip 213 will contact 50 with the elbow lever of the gong 217 and strike it, as a mere incident of such actuation, and call the attention of the operator to the fact that the motor is in condition for use. At the same time the catch 203 will be removed from under the latch 204 and thereafter the link 29 and the bar 21 can be depressed to couple the adding machine and motor together.

The controller 300 shown in Figs. 2, 8, 9, 60 10 and 11 is an invention forming the subject-matter of a co-pending application filed December 29, 1908, Serial No. 469,758. In its essentials it comprises a circular plate 419 provided with a hub 416 and radial slots 65 418. Radial pins 415 are fastened to the

hubs. A number of weights as shown at 75 are mounted to slide upon pins 415 and are further guided and limited in their movement by studs 417 which are fastened to the weights and project through the slots 418 70 in the plate 419. Springs 79 are attached to these studs and to the hub 416 as shown in Fig. 10, these springs tending to hold the weights in their extreme inner position abutting the hub. As shown in Fig. 8, the 75 weights have a peripheral projecting flange 700 which when the device is at rest or moving slowly is interposed in the path of movement of nose 291 of arm 290 rigidly fastened to shaft 31. The device is fastened to and rotates with shaft 101 so that when the latter acquires a predetermined speed, the centrifugal force acting upon the weights overcomes the tension of the springs to which they are attached and the weights 80 move radially outward thereby carrying the flange 700 out of the path of nose 291. The shaft 31 may then be rocked to cause the clutching action previously described.

It will thus be seen that we have provided a lock to prevent the depression of the bar 21 when the current is not on the motor and the latter cannot, therefore, actuate the adding machine and a second automatic lock operated from the motor to prevent the depression of the bar 21 until a proper speed has been arrived at to actuate the adding machine at the rate and under the conditions which should obtain for proper work.

What we claim as new is:

1. The combination with a motor a machine adapted to be intermittently operated by the motor, of an actuator by the movement of which the motor is coupled to the machine, a source of energy for the motor, a switch intermediate the same and the motor and means actuated from the switch adapted to hold the actuator inoperative so long as the motor is not energized.

2. The combination with a motor a machine adapted to be intermittently operated by the motor, of an actuator by the movement of which the motor is coupled to the machine, a source of energy for the motor, a switch intermediate the same and the motor, and means actuated from the switch adapted to hold the actuator inoperative so long as the motor is not energized, the same means serving to release the actuator as 110 an incident of the movement of the switch to energize the motor.

3. In combination, a calculating machine, an electrical motor, a connection between them including a depressible actuator, a source of energy from which the motor is energized, a switch and means actuated from the switch to engage the depressible actuator.

4. In combination, a calculating machine,

an electrical motor, a connection between them including a depressible actuator, a source of energy from which the motor is energized, a switch and means actuated from the switch to engage the depressible actuator when the circuit is broken by the movement of the switch.

5. In combination, a calculating machine, an electrical motor, a connection between them including a depressible actuator, a source of energy from which the motor is energized, a switch and means actuated from the switch to engage the depressible actuator when the circuit is broken by the switch 70 and automatically to disengage it when the circuit is closed.

6. In combination, a calculating machine, an electrical motor, a connection between them including a depressible actuator provided with a latch, a source of energy from which the motor is energized, a switch, and a catch moved by the switch to engage the latch and render it inoperative when the switch is actuated to break the circuit.

25 7. In combination, a calculating machine, an electrical motor, a connection between them including a depressible actuator provided with a latch, a source of energy from which the motor is energized, a switch, and a catch moved by the switch to engage the latch and render it inoperative when the switch is actuated to break the circuit, and also moved by the switch to release the latch when the switch is actuated to close the circuit.

30 8. The combination with a motor a machine adapted to be intermittently operated by the motor, of an actuator by the movement of which the motor is coupled to the machine, a source of energy for the motor, a switch intermediate the same and the motor and means actuated from the switch adapted to hold the actuator inoperative so long as the motor is not energized, and further means actuated by the same switch adapted to indicate visually that the motor is energized, as an incident of operating the switch for that purpose.

35 9. The combination with a motor a machine adapted to be intermittently operated by the motor, of an actuator by the movement of which the motor is coupled to the machine, a source of energy for the motor, a switch intermediate the same and the motor and means actuated from the switch adapted to hold the actuator inoperative so long as the motor is not energized, and further means actuated by the same switch adapted to indicate audibly 105 that the motor is energized, as an incident of operating the switch for that purpose.

40 10. The combination with a motor a machine adapted to be intermittently operated by the motor, of an actuator by the movement of which the motor is coupled to the

50 machine, a source of energy for the motor, a switch intermediate the same and the motor and means actuated from the switch adapted to hold the actuator inoperative so long as the motor is not energized, and further means actuated by the same switch adapted to indicate visually and audibly that the motor is energized, as an incident of operating the switch for that purpose.

55 11. In combination, a calculating machine, an electrical motor, a connection between them including an actuator, a source of energy from which the motor is energized, a switch and means actuated from the switch to engage the actuator when the circuit is broken by the switch, and simultaneously to indicate by a visual signal that the motor is not energized.

60 12. The combination with a motor a machine adapted to be intermittently operated by the motor, of an actuator by the movement of which the motor is coupled to the machine, a source of energy for the motor, a switch intermediate the same and the motor, a conductor leading from the source of energy to the motor through the switch and a light signal in the circuit.

65 13. The combination with a motor a machine adapted to be intermittently operated by the motor, of an actuator by the movement of which the motor is coupled to the machine, a source of energy for the motor, a switch intermediate the same and the motor, a conductor leading from the source of energy to the motor through the switch and a light signal in the circuit and an audible signal adapted to be mechanically operated by the switch when the latter is moved to close the circuit.

70 14. The combination with a motor a machine adapted to be intermittently operated by the motor, of an actuator by the movement of which the motor is coupled to the machine, a source of energy for the motor, a switch intermediate the same and the motor, a conductor leading from the source of energy to the motor through the switch and a light signal in the circuit and an audible signal adapted to be mechanically operated by the switch when the latter is moved to close the circuit, and means for automatically locking the actuator through the switch and extinguishing the light signal when the switch is moved to open the circuit.

75 15. In combination, a calculating machine, an electrical motor, a connection between them including a depressible actuator, a source of energy from which the motor is energized, a switch, means moved by the switch to hold the depressible actuator inoperative when the switch is actuated to break the circuit and to render it operative when the switch is actuated to close the circuit, and additional means rendering the depressible actuator inoperative after the motor is 120

80 85 90 95 100 105 110 115 120 125 130

energized until it has attained a predetermined speed.

16. In combination, a calculating machine, an electrical motor, a connection between them including a depressible actuator, a source of energy from which the motor is energized, a switch means moved by the switch to hold the depressible actuator inoperative when the switch is actuated to break the circuit and to render it operative when the switch is actuated to close the circuit, and additional means rendering the depressible actuator inoperative after the motor is energized until it has attained a predetermined speed and then permitting its operation.

17. The combination with a machine adapted to be intermittently operated by a motor, of an actuator by the movement of which the motor is coupled to the machine, a source of energy for the motor, a switch

intermediate the same and the motor, a conductor leading from the source of energy to the motor through the switch and a light signal in the circuit and an audible signal 25 adapted to be mechanically operated by the switch when the latter is moved to close the circuit, and means for automatically locking the actuator through the switch and extinguishing the light signal when the switch is 30 moved to open the circuit, the same means automatically rendering it inoperative when the speed of the motor falls below the predetermined rate.
